CHARLES E. SCRIBNER, OF CHICAGO, AND FRANK R. McBERTY, OF DOWNSERS GROVE, ILLINOIS, ASSIGNORS TO THE WESTERN ELECTRIC COMPANY, OF CHICAGO, ILLINOIS, A CORPORATION OF ILLINOIS.

TRUNK-LINE FOR TELEPHONE-EXCHANGES.

SPECIFICATION forming part of Letters Patent No. 787,120, dated April 11, 1905.

Application filed April 23, 1897. Serial No. 633,441.

To all whom it may concern:

Be it known that we, CHARLES E. SCRIBNER, residing at Chicago, in the county of Cook, and FRANK R. McBERTY, residing at Downers 5 Grove, in the county of DuPage, State of Illinois, citizens of the United States, have invented a certain new and useful Improvement 10 in Trunk-Lines for Telephone-Exchanges, of which the following is a full, clear, concise, and exact description, reference being had to the accompanying drawings, forming a part of this specification.

This invention concerns trunk-lines for uniting telephone-lines centering in different offices of an exchange, and applies to exchange systems comprising lines provided with signals in switchboards designed to be automatically responsive to currents in the lines determined in the use of the telephones at the 20 substations.

The general purpose and organization of this invention may be more clearly set forth after a brief description of the mode of establishing and conducting trunk connections between 25 lines entering different offices of an exchange prior to the invention.

It is common to provide signals in a telephone-switchboard for the lines centering in the switchboard and suitable arrangements of 30 circuits and sources of current to cause the operation of the signals as an incident to the use of the substation-telephones, the subscriber's act of taking the telephone for use serving to display a call-signal in the switchboard. It is further usual to associate with 35 each plug of a pair used in uniting lines thus equipped in the switchboard a signal which is controlled by the appliances at the station with whose line that plug is connected, so that 40 through observation of the two signals referring to the two plugs of a pair an operator is informed of the condition of the apparatus at both of the stations in communication. She is thus enabled to transmit any necessary call- 45 signals to either station and to effect discon-

nection of the lines immediately upon the return of both station-telephones to their idle condition. These signals are commonly termed "automatic supervisory signals." The trunk-lines heretofore in use have not been 50 adopted for uniting lines furnished with such signals, inasmuch as they afforded no means for operating supervisory signals in uniformity with the signals involved in local connections at both or all the offices traversed by the 55 complete connection.

The present invention aims to provide means for bringing the supervisory signal before the originating operator who initiates the trunk connection under control of the substation connected with the distant terminal of the trunk-line, and to provide a signal before the receiving operator, who completes the required connection to indicate to her also the 60 condition of the apparatus at the called station, the intention being to allow the originating operator to supervise the completed connection in a manner uniform with the supervision of local connections, but to permit the receiving operator to call the required station one or more times, as may be necessary, 65 in order that she may make any special or distinctive call, if required.

To this end this invention consists in the combination, with telephone-lines provided 70 with means for determining flow of current in the lines in the use of the substation-telephones and a trunk-line for making connection with the calling and with the called line, respectively, at its different terminals, of a 75 supervisory signal at the station of the originating operator and a supervisory signal at the station of the receiving operator, both of which signals are controlled from the called station.

It consists, further, in the combination, with such lines and the trunk-line, of two supervisory signals at the station of the originating operator, with means for controlling one of them from each of the united substations 80 85 90

and a supervisory signal at the station of the receiving operator controlled from the called substation.

The invention also furnishes the usual signals for disconnection for the trunk-line, with suitable means for operating such signals independently of the supervisory signals.

The invention is illustrated in the attached drawing, wherein two telephone-lines are represented entering different offices of an exchange system and provided with signals of different types in the switchboards thereof, together with a trunk-line extending between the offices and supervisory and clearing-out signals associated with the trunk-line.

The line conductors 1 and 2 at station A are united through two bridges, the former of which is permanently closed and includes a polarized bell *a* and a condenser *a'*, and the latter of which is normally open at a switch *a*² and includes the receiving-telephone *a*³ and the transmitting-telephone *a*⁴ at the station. The line conductors entering the central office B traverse the windings of a signal-controlling relay *b*, after which they are led to the pole of a battery *c* and to earth, respectively. The line conductors are represented in the switchboard by normally open terminals of the spring-jack *d*. The relay *b* controls the circuit through a signal-lamp *e*, placed near the spring-jack *d* in the switchboard. The local circuit comprises conductors 3 and 4, which lead to the poles of a local battery *f*. In the former of these conductors a resistance-coil *g* is interposed, while the latter includes the signal-lamp *e*. The conductors terminate in the normally separated contact-pieces of the relay. A branch 5 is led from the conductor 3 near its junction with the contact-piece of the relay to the thimble or ring contact *d'* of the spring-jack for the purpose of permitting the relay *b* to control a supervisory signal, which will presently be described. In the switchboard the usual pairs of connecting-plugs *h* and *h'* are provided each with three contact-pieces for registering with the three parts of the spring-jacks *d*. Those contact-pieces of the two plugs which make connection with the line-contacts of the spring-jack, the tip, and the short sleeve, respectively, are united by conductors 6 and 7, which constitute the plug-circuit. A condenser *i* is interposed in each of these conductors. The usual calling-key *k* is provided for disconnecting plug *h'* from its mate and connecting its line-contacts to the poles of a generator of calling-current, which is not shown in the drawing. A listening-key *l* is also furnished, by which the operator is enabled to connect her telephone *m* in a bridge of the plug-circuit. The sleeve-contact *n* of plug *h*, which makes connection with the thimble *d'* of a spring-jack when the plug is inserted therein, forms the terminal of a wire 8, leading to the same pole of battery *f* with which wire 4 is connected, and in this con-

70 tor a signal-lamp *o* is arranged, which is associated with the plug *h* in the switchboard. The contact-piece *n* of plug *h'* forms the terminal of a similar wire 9, which includes the signal *o'*, associated with plug *h'*. The connections of these local circuits are so arranged that when the plug *h*, for example, is inserted into the spring-jack *d*, the lamp *e* having been lighted to signify a call, the supervisory lamp *o* is brought into parallel with lamp *e* and diverts sufficient current from it to bring about the darkening of both lamps. Thereafter the breaking of the circuit through lamp *e* by the return of the station-telephone to its switch-hook at station A will permit the full current 80 through resistance-coil to traverse the lamp *o* and will cause the illumination of that lamp as a signal to the operator.

75 The apparatus at station A' is substantially the same as that at station A; but it is equipped with a magneto-generator *a*⁵, which is adapted to operate an annunciator *b'* in the switchboard at office C. The line conductors 1 and 2 of this line also are connected with the contact-pieces of a spring-jack *d*, which, however, 90 is arranged to cut off the annunciator *b'* when a plug is inserted into the spring-jack in the usual way.

85 A trunk-line 10 11 extends between the offices B and C. This line terminates at the office B in a spring-jack *p*, adapted for use with the plug *h'*, and at the office C in a plug *q*, constructed for use with the spring-jacks *d* in that office. From the conductor 11 of this trunk-line, which is intended to be brought 100 into connection with the shorter sleeve of plug *h'*, a ground branch 12 is taken at office B. A relay *r* is interposed in this ground branch, with a magnet of high impedance, together with a battery *s* or other source of current. This relay controls the continuity of a circuit 13 14, the former wire of which leads to the same pole of battery *f* with which wire 3 of the local signal-circuits is connected and includes a resistance-coil *g'* and the latter 110 of which leads to the thimble *d'* of spring-jack *p*. A similar earth branch 15 is taken from wire 11 at station C, in which, likewise, a relay *r'* and a source of current *s'* are interposed. This latter relay controls a local circuit including a source of current *t*, together with a signal-lamp *u*, which is controlled also by a plug-seat switch *v* in the seat or socket of plug *q*. This local circuit is made up of wires, 16 leading from one pole of the battery to one contact-piece of the relay, 17 from the other contact of the relay to one terminal of the lamp *u*, 18 from the other terminal of the lamp *u* to one contact-piece of the plug-seat switch *v*, 19 completing the circuit from 120 the other contact-piece of the plug-seat switch to the other terminal of the battery *t*. It is obvious that when the plug *q* is removed from its socket the break between wires 18 and 19 becomes closed, after which the lamp *u* will 130

be lighted as long as the relay r' is inert. The shorter spring d^2 of trunk-jack p (that which forms the terminal of conductor 10 of the trunk-line) is furnished with an anvil d^3 , against which it is thrust when a plug is inserted in the spring-jack. From this anvil d^3 an earth branch 20 is led, which includes a source of current w together with an impedance-coil. To operate in conjunction with this source of current, a relay w is located in a ground branch 21 from conductor 10 at station C. This relay determines the continuity of a local circuit, which includes another signal-lamp u' , associated with the plug q , this circuit also being controlled by the plug-seat switch v . The local circuit is made up of wires, 22 leading from wire 16 to one contact-piece of the relay, 23 leading from the other contact-piece of the relay to one terminal of lamp u' , and 24 extending from the other terminal of the lamp to wire 18, whence it finds circuit to battery t through the plug-seat switch and wire 19. Lamp u' will therefore also be lighted when the plug q is removed from its seat while the relay w is inert.

The receiving operator at office C is furnished with the usual calling-key k' for looping a generator of calling-current into circuit with plug q . She has also a telephone m' , which is connected by an order-circuit 25 with the operator's telephone m at station B, the continuity of the order-circuit being controlled by a key y at the latter office in the usual way.

In the normal condition of the apparatus the signals are all inert, the relays being in the positions shown in the drawings. The circuit through the line-lamp e is open at the switch-contacts of relay b . The circuits through the supervisory lamps u and u' are closed as respects the relays which control them, respectively, but are open at the plug-seat switch v .

The trunk-circuit is adapted for use in extending connections from line from station A entering office B as a calling-line to station A', connected with the office C as a correspondent station. The office B is termed the "originating" office, and the connection after its establishment is supervised at that station. The office C is termed the "receiving" office, and the work done there is merely that of placing the plug q in the spring-jack d in compliance with an order sending a call to the required station, and, finally, removing the plug from the spring-jack to discontinue the connection. It will be understood that other lines similar to that from station A terminate at the office B and that such lines may be united ordinarily by means of the plugs h and h' and their plug-circuits furnished the operator at that office. Similarly other stations A' have lines leading into office C, where also local connections may be established by means of the usual appliances. (Not shown.)

5 The process of securing connection between

stations A and A' and the supervision of the completed connection is as follows: The receiving-telephone a^3 is removed from its switch a^2 at station A, whereby a closed path is provided at the station for current from 70 battery c . The current produced in this path excites the relay b , which closes the local circuit 3 4 and lights the lamp e . The operator at office B, answering the call, inserts plug h into the spring-jack d and connects her telephone with the plug-circuit 6 7 by means of listening-key l . The insertion of the plug in the spring-jack brings the supervisory lamp o into parallel with the line-lamp e , whereby 75 a sufficient current is diverted from the line-lamp to render it dark. The calling party at station A gives his order to the operator at office B orally, following which the operator connects her telephone with the call-wire 25, leading to the operator at office C, wherein 80 the line called for terminates, and instructs the operator there to connect a trunk-line with the line to station A'. In pursuance of a well-known mode of operating the operator at office C, knowing what trunk-lines between 85 office C and office B are idle, designates to the originating operator at office B the trunk-line which is to be employed. The originating operator then inserts plug h' into spring-jack p of that trunk-line, whereby the line-circuit 1 2 is extended through the plug-circuit 6 7 to the line conductors 10 11 of the trunk-line. The plug and spring-jack together constitute what we term a "connection-switch," whereby one circuit may be united 90 with the other. Simultaneously the receiving operator at office C inserts the terminal plug q of the same trunk-line into the spring-jack d of the called line, after which she depresses the ringing-key k' , and thus transmits a signaling-current to ring the bell a at 95 station A'. In these different acts the following changes are brought about in the local circuits associated with the plug-circuit 6 7 and the trunk-line 10 11: The conductor 9, 100 through the supervisory lamp o' , associated with the plug-circuit, becomes connected with conductors 14 and 13 to form a local circuit including the supervisory lamp and controlled by the switch-contacts of relay r . Inasmuch 105 as no current as yet exists through that relay, the conductor 7 being interrupted at the condenser i and the conductor 11 being united to the open conductor 2 of line to station A', this 110 local circuit 9 14 13 is closed and the supervisory signal o' is lighted. At the receiving office C the removal of the plug q from its seat makes connection between wires 18 and 19, 115 whereby a complete circuit is formed through supervisory lamp u , made up of wires 16, 17, 18, 120 and 19, the relay r' being inert on account of the same circuit conditions before traced as affecting the relay r . Hence the supervisory lamp u before the receiving operator also is lighted. 125 The insertion of plug k' into spring-jack p 130

1

forces the spring d^2 against its anvil d^3 and brings the conductor 20 into a branch from line conductor 10 of the trunk-line. This change of circuit permits current to flow from battery 5 w through wires 20, 10, and 21, which excites the relay x and effects the separation of its switch-contacts. Hence although the local circuit including the lamp u' is closed at the plug-seat switch v it is broken at the switch-contacts of relay x , and the lamp u' remains dark. The condition of the signals immediately after the completion of the connection is then briefly: The line-lamp e of the calling-line is dark. The supervisory lamp o 15 is dark, indicating to the supervising operator that the telephone at station A is in use. The supervisory lamp o' is lighted, signifying to the supervising operator that the telephone at the called station A' is still on its switch. 20 The supervisory lamp u before the receiving operator is lighted, signifying to that operator that the call transmitted to station A' has not yet received attention. If the signal u should remain lighted for any unreasonable 25 length of time, the receiving operator should transmit a second call. If the line to station A' be a party-line or if it require any other specialized mode of calling, the operator at office C, who is accustomed to make connection with the line, may take any necessary steps in transmitting the call. When the subscriber at station A' removes the receiving-telephone from its switch a^2 in response to the call, the line-circuit 1 2 is completed 30 through the conductor, including the telephones. A path is thus furnished for current from both batteries s and s' into conductor 11 of the trunk-line, thence over line-wire 2, returning by line-wire 1, and finding circuit to earth through the relay x . Both relays r and r' then become excited and attract their armatures, breaking the local circuits which they control. Thus the supervisory lamp o' at office B and the supervisory lamp 35 u at office C both become dark. Their extinction signifies to both the supervising and receiving operators that the called subscriber has answered. As long as the supervisory lamps remain in this condition the operators 40 understand that the lines are in use. When at the termination of conversation the subscribers at stations A and A' replace their telephones on the switches, the relays b , r , and r' become inert. The relay b in breaking the circuit 3 4 diverts the full current of battery f through the resistance-coil g into the supervisory lamp o , whereby that lamp becomes lighted. The relay r in releasing its armature closes the circuit 9 14 13, causing 45 the illumination of supervisory lamp o' . The simultaneous illumination of supervisory lamps o and o' signifies to the supervising operator that the connection may be broken and is therefore followed by the removal of 50 plugs h and h' from the spring-jacks d and

p . The removal of plug h' from trunk-jack p severs the connection of earth branch 20 with conductor 10 of the trunk-line, whereby the relay x is deprived of current, the connection of batteries s and s' with the conductor 10 through the medium of line-wires 1 and 2 having been previously broken. When this relay permits its lever to fall against its contact-anvil, current flows in the circuit through clearing-out lamp u' , lighting that lamp. The simultaneous lighting of lamps u and u' before the receiving operator is a call for disconnection of the trunk-line and is followed by the removal of the plug q from the spring-jack d and the return of the plug to its seat. Thus the supervising operator at the originating office is provided with a group of supervisory signals identical in arrangement and mode of operation with those which she uses in ordinary local connections, so that no special work is required on her part in supervising trunk connections. Likewise the receiving operator at office C is furnished with a signal which denotes to her the response of the called subscriber, whereby she is enabled to send any specialized signal that may be required in case the subscriber fails to respond to the first call. She has also a distinct clearing-out signal calling for the removal of the trunk connection.

We claim as the invention—

1. The combination with a calling and a called telephone-line and a trunk-line uniting them, of a continuously-operative source of current connected with the lines, a telephone-switch at the substation of the called line, operated automatically in the use of the telephone apparatus thereat and controlling the flow of current in the line, and supervisory signal devices one at each terminal of the trunk-line, operated through the agency of the current so controlled, whereby the condition of use or disuse of the substation telephone apparatus during connection is constantly indicated at both terminals of the trunk-line.

2. The combination with two telephone-lines and means for producing current therein, each line having a telephone-switch at the substation thereof, operated automatically in the use of the substation telephone apparatus, controlling the flow of current in the corresponding line, of a trunk-line uniting said telephone-lines, two supervisory signal devices at one terminal of the trunk-line responsive to the telephone-switches at the respective substations, and a supervisory signal at the other terminal of the trunk-line responsive to the telephone-switch at the substation of the corresponding line.

3. The combination with two telephone-lines, each provided with means for automatically determining the flow of current in the line in the use of the telephone, a trunk-line connected at one terminal with one of the

lines, and a pair of plugs and the plug-circuit thereof uniting the other terminal of the trunk-line with the other line, of a supervisory signal for each plug of the pair, and 5 means for controlling one of said signals through the agency of current in each of the telephone-lines, and a supervisory signal at the terminal of the trunk-line distant from said plugs, said last-mentioned signal being 10 controlled by current in the line with which said terminal of the trunk-line is directly connected, as described.

4. The combination with two telephone-lines, of a trunk-line uniting the lines, a calling-key in the trunk-line at one terminal station thereof adapted to transmit a call-signal to the station of one of the lines, a supervisory signal at each terminal of the trunk-line, circuits including the said signals together 15 with sources of current associated with the said trunk-line, and means for closing the signal-circuit to operate both of said signals in the use of the telephone at the said called station; whereby both operators are informed of 20 the response to the call at a called station, as described.

5. The combination with two subscribers' telephone-lines, of a trunk-line 10 11, connection-switches at each terminal of the trunk-line for telephonically uniting said subscribers' lines through the trunk-line, an induction device interposed in the circuit near one terminal of the trunk-line, a telephone-switch controlling the circuit at the substation of the 15 line which is connected to the other terminal of said trunk-line, branches 12 15 to a return-conductor from one trunk-wire 11 near the respective terminals thereof, a signal-controlling magnet and a battery in each of said 20 branches, the batteries being opposed, a signal-controlling magnet in a branch to said return-conductor from the other trunk-wire 10 near one terminal, and a battery *w* applied to the said wire 10 at the other terminal in closing 25 the connection-switch therat.

6. The combination with two telephone-lines, each having means at its station for determining the flow of current in the line in the use of the telephone, and a trunk-line 50 uniting the lines, of three relays connected with the circuit to respond to current in the lines, a device adapted to transmit telephonic currents but to prevent the flow of continuous currents interposed in the circuit between two 55 of the relays to bring one of the relays under control of one of the substations and the other relays under the control of the other substation, and supervisory signals controlled by the relays, the supervisory signals which are controlled 60 from the same station being associated with opposite terminals of the trunk-line, as described.

7. The combination with two telephone-lines, each provided with means at its substation 65 for determining the flow of current in the

line in the use of the telephone, said lines entering different switchboards, a trunk-line between the switchboards having one terminal directly connected with one of the lines, and a pair of plugs and a plug-circuit uniting the other terminal of the trunk-line with the other telephone-line, of relays connected with the circuit, and supervisory signals associated with the connecting-plugs controlled by the 70 said relays, a device interposed in the plug-circuit adapted to render the relays independently responsive to currents in the different telephone-lines, a calling-key in the trunk-line circuit at the terminal thereof distant from the plug-circuit, a relay connected with the 75 circuit near the same point, and a supervisory signal associated with the trunk-line controlled by the said last-mentioned relay, said relay being responsive to current in the called line only, as described.

8. The combination with two telephone-lines, each provided at its substation with a switch for closing the line during the use of the telephone, and a trunk-line uniting the telephone-lines, of two relays connected with 90 the circuit near one terminal of the trunk-line, supervisory signals controlled by the relays, sources of current adapted to produce current through the relays and lines when the line-circuits are closed at the substations, and a device in the circuit intermediate of the relays adapted to prevent current in either line from affecting the relay associated with the other line, a calling-key at the other terminal of the 95 trunk-line, a relay connected with the circuit 100 at the same terminal adapted to respond to current in the line with which said terminal is directly connected, and a supervisory signal controlled by that relay, substantially as described.

9. The combination with telephone-lines provided at their substations with means for closing the line-circuits during the use of the telephones, a plug-circuit and a trunk-line uniting the telephone-lines in complete circuit, of condensers in the plug-circuit, a bridge of the circuit at each side of the condenser, and a relay and a source of current included therein, a supervisory signal associated with each plug of the circuit controlled by the relay, a second bridge of the circuit at the distant terminal of the trunk-line, and a relay and a source of current therein, and a supervisory signal controlled by said second-mentioned relay, as described.

10. The combination with two telephone-lines, each provided at its substation with means for determining the flow of current in the line in the use of the telephone, a plug-circuit and a trunk-line uniting the telephone-lines in a complete circuit, a supervisory signal associated with each terminal plug of the plug-circuit, the different signals being controlled by current in the different telephone-lines, a supervisory signal at the other termi- 125 130

nal of the trunk-line controlled by current in the line with which said terminal is directly connected, a clearing-out signal associated with said last-mentioned terminal of the trunk-line, and a circuit changed in the act of making connection with the other terminal of the line determining the actuation of said clearing-out signal, substantially as described.

11. The combination with a calling and a called line and a trunk-line uniting them, of means adapted to produce current in the lines, supervisory signal devices, one at each terminal of the trunk-line, a telephone-switch at the substation of the called line, operated automatically in the use of the telephone apparatus thereat, and controlling the flow of

current in the line, and means adapted when said switch is raised to withdraw said signal devices, and when depressed to display the same; whereby the condition of use or disuse of the substation telephone apparatus of the called line is automatically indicated at both the terminals of the trunk-line.

In witness whereof we have hereunto subscribed our names this 2d day of March, A. D. 25 1897.
